UNITED STATES PATENT OFFICE.

JOHN M. WILCOX, OF CLEVELAND, OHIO.

PUNCHING AND SHEARING MACHINE.

1,356,248.

Specification of Letters Patent. Patented Oct. 19, 1920.

Application filed March 4, 1920. Serial No. 363,217.

To all whom it may concern:

Be it known that I, JOHN M. WILCOX, a citizen of the United States, residing at Cleveland, in the county of Cuyahoga and State of Ohio, have invented a certain new and useful Improvement in Punching and Shearing Machines, of which the following is a full, clear, and exact description, reference being had to the accompanying drawings.

This invention relates to punching and shearing machines and more particularly to that class of machines which employ toggle blocks for actuating the movable member.

Heretofore it has been the custom with machines of this character to complete the punching or shearing operation with a single stroke of the toggle, and because of the enormous instantaneous stresses set up during this operation, it has been necessary to build a machine of unusually large size and heavy weight. Such machines are usually stationary and when large and unshapely material is to be accurately positioned under the movable member, a large number of men are required to steady the material in addition to the crane which supports the weight thereof.

It is the object of my invention, therefore, to provide a machine capable of exerting the required force for punching said holes and yet consist of so few and simple parts as will be sufficiently light in weight to permit carrying the machine to the work by a small crane or other support and there be accurately and quickly positioned on the center punch mark with the help of only one or two men.

Another object is to provide a machine of this character which shall be so constructed that it will exert a maximum punching effort with a minimum input of power.

Another object is to provide a novel feed device whereby the punch is enabled to exert a plurality of strokes in overcoming the shearing stress of the material to be punched.

Another object is to provide a device which will quickly clear the punching from the hole and return the parts to normal position for the next punching operation.

With these and other objects in view, the invention consists of the various novel features of construction and combination, all

of which will be fully described hereinafter and pointed out in the claims hereto annexed.

In the accompanying drawings wherein I have shown certain illustrative embodiments of my invention but without intent to limit myself thereto, Figure 1 is a side elevation of my machine; Fig. 2 is a top plan view thereof; Fig. 3 is a section taken on the line 3—3 of Fig. 1; Fig. 4 is an enlarged section taken on the line 4—4 of Fig. 3; Fig. 5 is a detail view of one form of toggle actuating mechanism; Fig. 6 is a detail sectional view of the auxiliary punch actuating mechanism; Fig. 7 is a side elevation of a modification of the toggle actuating mechanism; and Fig. 8 is a top plan view thereof.

Describing the various parts by reference characters, 1 indicates the side frames of my machine which are held in spaced relation by suitable transverse bolts 2 and also by the toggle actuating mechanism interposed therebetween which will be fully described hereinafter. A pair of toggle members 3—3 are pivotally connected at their lower ends to the cross head 4, which is slidably mounted in the bearing block 5, the latter being fastened between the side frames 1. At their upper ends the toggles 3—3 are each pivotally connected to the toggle blocks 6—6 and these blocks slidably abut the wedge shaped feed blocks 7—7. A U-shaped strap 8 surrounds the toggle mechanism and is securely fastened at each end to the side frames 1 as indicated at 10. Disposed about the upper end of the U-shaped strap 8, is a collar 11 from which projects the feed screw 12. Each of the feed blocks 7—7 is connected at their larger end by a transverse arm 13, and a hand wheel 14 is rotatably journaled therein intermediate the end thereof and in alignment with the feed screw 12. It will thus be apparent that as the hand wheel 14 is rotated on the screw 12 to advance inwardly toward the collar 11, the feed blocks 7—7 will be moved inwardly simultaneously and force the toggles downwardly.

A pair of arms 16—16 are each pivotally connected at one end to each of the pivotal joints 17—17 of the toggles and at the other end each arm is connected to the respective bellcranks 18—18 journaled on a common

shaft 19 which is mounted in the vertical brackets 20-20. Disposed on the side frames 1 and rearwardly of the brackets 20-20 are a pair of bearing blocks 21-21 which rotatably support the shaft 22 the outer end of which has keyed thereto a worm gear wheel 23. A pair of cam disks 24-24 are fastened to the shaft intermediate the side frames 1-1 and each cam disk is provided with a strap 25, the upper ends of which are pivotally and adjustably connected with each of the bellcranks 18-18. The cam disks are preferably so positioned on shaft 22 as to be in opposite phase so that when one toggle member is straight, the other will be relaxed to its maximum degree. A bracket 27 is fastened to the rear end of one of the side frames 1 and supports any suitable source of power such as an electric or air motor 28 which is provided with a worm drive wheel 29 adapted to mesh with the worm gear 23.

The forward end of the side frames 1 are each provided with an integrally formed projection 31 which supports a cylinder 32. A piston 33 is slidably mounted therein and is provided with a connecting rod 34 which is connected at its lower end to an arm 35 preferably formed integral with a vertical shaft 36 which is positioned under the cross head 4. Fluid under pressure is admitted from the supply line 37, through the valve 38 to the pipe line 39 leading to the cylinder head. A by-pass 40 provided with a check valve 41 communicates with the middle and lower portion of the cylinder so that when the piston 33 passes the upper branch thereof, the fluid will escape therethrough and cushion the descent of the piston 40 ton. When the valve 38 is rocked in the opposite direction the fluid supply line 37 is connected through the pipe 42 to the lower end of the cylinder to force the piston 33 upwardly; the check valve 41 preventing 45 the by-pass from functioning. Suitable pet-cocks 43, 44 are tapped in the pipes 39 and 42, respectively, to relieve any back pressure or vacuum which may be created by the movement of the piston 33.

50 A bail 45 is preferably attached to the side plates 1-1 at the center of gravity of the machine so as to permit easy handling thereof with the aid of a small crane. A pair of guide rollers 46-46 are journaled each in one of the arms 47-47 which are adjustably attached to the projections 31-31 thereby facilitating the movement of the machine over the work. The punch 48 is detachably connected to the vertical shaft 36 by a coupling nut 49 to permit various sized punches, shearing blades or similar tools to be used.

In operation, the machine is suspended over the work by the bail 45 and the guide rollers 46-46 adjusted to the surface there-

of. Since the machine is comparatively small and light in weight it may be accurately and quickly positioned over the center mark of the hole to be punched, by one man, while a second man operates the machine in the following manner: Valve 38 is rotated to cause piston 33 to descend which carries the punch down to the center mark as previously described. The motor is now started which rotates gear 23 and shaft 22 thereby oscillating the bell-crank 18-18 through the medium of cams 24-24 causing the toggles 3-3 to break and straighten alternately. The hand wheel 14 is now rotated to feed the toggle blocks and toggles downwardly until the cross head 4 contacts with the shaft 36. As each toggle straightens the punch 48 is forced downwardly into the metal. The hand wheel 14 is rotated slowly to take up the downward movement of each toggle until the shearing stress of the metal is overcome, at which time the pressure which has been continuously applied to the top of piston 33 will force the punched blank through the hole. A collar 52 which is fastened to the cross head 4 above the bearing block 5 prevents the cross head and toggle mechanism from descending farther with the punch. The operator now reverses the valve 38 which forces piston 33 and punch 48 upwardly to clear the hole when the machine may be moved to the next punch mark.

The adjustable connection between the bellcranks 18-18 and cams 25-25 permit a maximum and minimum stroke of the toggles, the former to be used on light work where the shearing stress of the metal is not so great, and the latter on heavy work where the shearing stress is high and a short stroke more advantageous.

In Figs. 7 and 8, I have shown a modification of the toggle actuating mechanism, wherein a single cam disk 60 is mounted on the shaft 22^a. The toggles 61-61 are mounted to break alternately in opposite directions and each is connected to one of the angularly disposed arms 62-62 by a link 63. The arms 62-62 are rigidly mounted on shaft 19^a and a single arm 63^a also rigidly fastened thereto extends rearwardly therefrom. An adjustable rider 64 is slidably mounted on the arm 63 and is pivotally connected at the lower end thereof to the cam strap 65. Adjustment of the rider and hence the effective length of arm 63^a is effected by the screw 66 swiveled in projection 67 of arm 63^a and threaded in the top portion of the rider. The operation is similar to that previously described except that the stroke of the punch 48 is varied by the screw 66 instead of the adjustable connection between the bellcranks, and the cam straps.

While I have described my machine as

being swung from a crane and adapted for a particular use, it will be understood that it may be bolted down in the usual manner and that various tools may be substituted for the punch.

Having thus described my invention, what I claim is:

1. A device of the class described comprising a support, a toggle member mounted 10 in said support, means for connecting a tool to one end of said toggle, a feed device positioned in operative relation to said toggle member and adapted to feed said member and tool through the work in a direction 15 parallel to the line of thrust of said tool, and means for actuating said toggle.

2. A device of the class described comprising a support, a toggle member mounted in said support, means for actuating said 20 toggle, a tool operatively connected to the lower end of said toggle, a feed device positioned in operative relation to said toggle member and adapted to feed said member and tool through the work, and means for 25 exerting an additional force on said tool.

3. A device of the class described comprising a support, a plurality of toggles slidably mounted in said support, a tool operatively connected to said toggles, eccentric 30 means for alternately actuating said toggles, a wedge block for moving said toggles and said tool into operative engagement with the work and means for exerting an additional force on said tool.

35 4. A device of the class described comprising a support, a plurality of toggle members mounted in said support, a tool operatively connected to said toggles, means for actuating said toggles alternately, and a feed device for moving said toggles and said tool in operative engagement with the work.

5. A device of the class described comprising a support, a plurality of toggles 45 slidably mounted in said support, a tool operatively connected to said toggles, eccentric means for successively actuating said toggles, a wedge block for moving said toggles and said tool into operative engagement with the work and means for varying 50 the stroke of said toggles.

6. A device of the class described comprising a support, a plurality of toggles mounted in said support and adapted to 55 break and straighten alternately, a tool disposed in operative relation to said toggles, a cylinder mounted on said support, a piston slidably mounted in said cylinder and operatively connected to said tool, and fluid 60 pressure means for actuating said piston.

7. A device of the class described comprising a support, a plurality of toggle members mounted in said support, a tool operatively connected to said toggles, means 65 for actuating said toggles, a feed device for

moving said toggles and said tool in successive steps through the work, and means for varying the stroke of said toggles.

8. A device of the class described comprising a support, a plurality of toggles 70 mounted in said support and adapted to break and straighten alternately, a tool disposed in operative relation to said toggles, and means for exerting a force independent of said toggles on said tool.

75 9. In a device of the class described, the combination of a support, of a pair of toggles slidably mounted in said support, eccentric means for actuating said toggles alternately involving a pair of cams each 80 adjustably connected to said toggles, a tool operatively connected to said toggles and means for feeding said toggles and said tool into operative relation to the work.

10. In a device of the class described, the 85 combination with a support, of a plurality of toggles mounted therein, an eccentric mounted on said support and adapted to be rotated, operative connections between said eccentric and each of said toggles and means 90 for adjusting said connections to vary the stroke of said toggles.

11. In a device of the class described, the combination with a support provided with a plurality of toggles slidably mounted 95 therein, of a tool disposed in operative relation to said toggles, and means independent of said toggles for exerting a force on said tool and for returning said parts to normal position.

100 12. In a device of the class described, the combination of a support provided with a pair of toggles slidably mounted therein, of a tool operatively connected to one end of said toggles, a taper block slidably 105 mounted at the other end of said toggles, and adapted to move said toggles and tool bodily into engagement with the work, means for adjusting said block relative to said toggles and means for operating said toggles.

115 13. In a device of the class described, the combination with a support, of a pair of toggles slidably mounted in said support, means for adjusting the stroke of said toggles, a tool operatively connected to said toggles and means for exerting a force on said tool in addition to that exerted by said toggles.

120 14. In a device of the class described, the combination with a support, of a pair of toggles slidably mounted in said support, and fluid actuated means for adjusting said toggles relatively to the work independent of the actuating means for said toggles.

125 15. In a device of the class described, the combination with a support, of a tool slidably mounted in said support, and means for advancing said tool in successive steps through the work.

16. In a device of the class described, the combination with a support, of a tool slidably mounted in said support, means for engaging said tool with the work, and additional means for advancing said tool in successive steps through the work.

17. In a device of the class described, the combination with a support, of a tool slid-

ably mounted in said support, means for engaging said tool with the work, and additional means for delivering successive impulses to said tool. 10

In testimony whereof, I hereunto affix my signature.

JOHN M. WILCOX.
